J. Bastion,

Water Wheel.

N° 14,793.

Patented May 6, 1856.

Fig. 1.

Fig. 2.

UNITED STATES PATENT OFFICE.

JOSEPH BASTION, OF THERESA, NEW YORK.

IMPROVED CONSTRUCTION OF GUIDES OR CHUTES FOR TURBINE WHEELS.

Specification forming part of Letters Patent No. 14,793, dated May 6, 1856.

To all whom it may concern:

Be it known that I, JOSEPH BASTION, of Theresa, in the county of Jefferson and State of New York, have invented certain new and useful Improvements in Constructing Chutes for Turbine Water-Wheels; and I do hereby declare that the following is a full and exact description of the same, reference being had to the accompanying drawings, and to the letters of reference marked thereon.

The nature of my invention consists in a new and improved mode of constructing the chute for turbine water-wheels, which mode enables me to impart the proper direction to the water when coming in contact with the wheel, also to regulate and govern the quantity of water discharged in a specified length of time.

To enable others skilled in the art to make and use my invention, I will proceed to describe its construction and operation.

Figure 1 is a top or plan view of the chute with same being open for the passage of the water to the wheel. Fig. 2 is an inverted view with the chute closed.

Similar figures in the several views refer to similar parts.

A represents a plank of suitable dimensions, to which I secure the stationary part of the chute.

B represents a conical center having an aperture in the top through which the wheel-shaft passes, said center being held in a stationary position by means of curved supporters C C, Fig. 2, which perform the double purpose of supporting the conical center and acting in conjunction with the movable part for graduating or closing the chute. Said supporters are provided with a flange c c, as seen in Fig. 2, which forms an entire circle and is secured to the plank by any suitable means, thus giving permanency to the supporters C C and center B.

D E F are the adjustable part of the chute, which in form somewhat resembles the frustum of a cone inverted, the minor base of

which if it were a perfect frustum would closely encircle the base of the conical center; but it may be seen by examining Fig. 1 that the parts D D are in the form of a true cone and that the parts E E form part of a circle of a diameter less than that of the cone D D's base. By this arrangement it may be seen that I form a chute H through the side of the cone, which imparts the desired direction to the water as it passes to the wheel. The flange g supports the movable or adjustable part of the chute and keeps it in place, said flange g being secured between flange c, Fig. 2, and segments J J, Fig. 1. K is a stop on flange g, which comes in contact with segment J when it is closed. The conical parts D D, Fig. 1, correspond in their inclination and curvature with supporters C C, Fig. 2, and fit closely to them when the chute is open.

Fig. 1 represents the chute open. Now, to close the same we have only to revolve the movable part in the direction of the arrow, Fig. 1, until parts D D shall assume the position as shown in Fig. 2.

To graduate the quantity of water discharged to any desired volume, we have only to adjust the movable part accordingly.

Having thus fully described the construction and operation of my invention, what I claim as new, and desire to secure by Letters Patent, is—

The stationary conical center B, in combination with the adjustable parts D E F and supporters C C for the purpose of graduating the quantity of water discharged and giving the desired direction to the same, the whole being constructed and arranged as herein described.

In testimony whereof I have hereunto set my hand and affixed my seal this 24th day of March, 1856.

JOSEPH BASTION. [L. S.]
